UNITED STATES PATENT OFFICE.

WILLIAM MORRIS, OF JACKSON, NEBRASKA.

MORTAR-HOE.

1,197,530.

Specification of Letters Patent. Patented Sept. 5, 1916.

Application filed February 11, 1916. Serial No. 77,722.

To all whom it may concern:

Be it known that I, WILLIAM MORRIS, a citizen of the United States, residing at Jackson, in the county of Dakota, State of Nebraska, have invented certain new and useful Improvements in Mortar-Hoes; and I do hereby declare the following to be a full, clear, and exact description of the invention, such as will enable others skilled 10 in the art to which it appertains to make and use the same.

This invention relates to improvements in hoes, and particularly to mortar hoes.

One object of the invention is to provide 15 a mortar hoe by means of which mortar can be more thoroughly and intimately mixed than with the ordinary hoes now used.

Another object is to provide a hoe of this 20 description which can be manufactured and sold at a comparatively low cost, and which will be easy and effective in operation.

Other objects and advantages will be apparent from the following description when taken in connection with the accompanying 25 drawing.

In the drawing: Figure 1 is a front elevation of a hoe made in accordance with my invention. Fig. 2 is a rear elevation of the same. Fig. 3 is a horizontal sectional view 30 on the line 3—3 of Fig. 1, and Fig. 4 is a horizontal sectional view on the line 4—4 of Fig. 1.

Referring particularly to the accompanying drawing 10 represents the blade 35 or body of the hoe, which is formed from a single blank of suitable metal. Formed in the blade, and extending longitudinally thereof are three rows of openings 11, 12 and 13, the former of which are circular in 40 outline. The row of openings 12 are formed by striking out a plurality of tongues or webs 12' on the forward face of the hoe blade which extend therefrom at an angle. The openings 13 are similarly formed but 45 the tongues or webs 13' are also formed to extend at an angle to the front face of the blade and in opposite direction to the webs 12'. All of these webs extend transversely across the openings, as clearly seen in the 50 sectional views. The vertical sides of the

blade are turned rearwardly as shown at 14 for the purpose of preventing mortar passing around the sides of the blade as the blade is drawn through the mortar and toward the operator. The blade is equipped 55 with a suitable handle 15 by means of which the same is manipulated through the mortar. It will thus be seen that as the blade is drawn toward the operator, and through the mortar, some of the mortar will pass 60 through the openings 13, and engaging against the webs 13' will be deflected toward the right, and some will pass through the openings 12, and engaging the webs 12' will be deflected toward the left in overlapping relation to that deflected by the webs 13'. Thus the mortar will be deflected first in one direction, and then in the other, so that it will be more intimately 65 mixed, and more finely divided, than with 70 hoes of ordinary construction. It will of course be understood that mortar will also pass through the openings 11 in both directions of movement of the blade, so that the portion of mortar above the upper line 75 of openings 12 will fall onto the mass which is passed through the openings 12 and 13 and also be deflected by the webs. Furthermore, this will give the same effect as the lifting action given with the ordinary hoe 80 when it is passed through the mortar.

What is claimed is:

1. A mortar hoe comprising a blade formed with a plurality of rows of openings and deflecting webs, one row of openings having forwardly extending and laterally directed deflecting webs, another row of openings having forwardly extending and laterally directed webs extending in a direction opposite to those of the before- 90 mentioned row, and rearwardly directed guard flanges on the sides of the blade.

2. A mortar hoe comprising a blade formed with a plurality of horizontal rows of openings and deflecting webs, the upper 95 row of openings being formed to extend through the hoe blade at right angles to the plane of its front face, the next lower row of openings having forwardly and laterally directed deflecting webs, while the next 100

lower row of openings is provided with forwardly and laterally directed deflecting webs extending in opposite direction to those of the above row, and rearwardly 5 directed guard flanges on the sides of the blade.

In testimony whereof, I affix my signature, in the presence of two witnesses.

WILLIAM MORRIS.
